UNITED STATES PATENT OFFICE.

SAMUEL H. GOLDSTEIN, OF PHILADELPHIA, PENNSYLVANIA.

STOP-MOTION.

1,394,546.

Specification of Letters Patent. Patented Oct. 25, 1921.

Application filed August 15, 1921. Serial No. 492,384.

To all whom it may concern:

Be it known that I, SAMUEL H. GOLDSTEIN, a citizen of the United States, residing in Philadelphia, Pennsylvania, have invented 5 the Stop-Motion, of which the following is a specification.

One object of this invention is to provide a relatively simple, inexpensive and compact device which shall be controlled by a 10 thread and which shall be automatically actuated upon breakage or slackening of said thread to stop the machine to which the latter is normally delivered.

I further desire to provide a stop motion 15 which shall be certain and sensitive in its action, not likely to get out of order, which may be easily reset after operating and which shall exert a minimum stress upon the thread by which it is controlled.

These objects and other advantageous ends 20 I attain as hereinafter set forth, reference being had to the accompanying drawings, in which,

Figures 1 and 2 are respectively side and 25 end elevations of a stop motion constructed in accordance with my invention; and

Figs. 3 and 4 are elevations of the stop motion shown in Figs. 1 and 2 with the cover 30 of the casing removed showing the parts in their set and in their released positions respectively.

In the above drawings, 1 represents a rod or bar forming a part of or connected to a 35 bobbin stand or some relatively fixed part of a knitting machine, and 2 is a relatively movable part of the same machine such as the rotary gear ring or other rotary element having a series of holes of which one is indicated at 3.

40 In accordance with my invention I mount on the bar or rod 1 a casing 4 held to it in the present instance by a pair of integral collars 5, each of which is equipped with a set screw 6 for holding said casing im-

45 movably in place. The casing is provided with a cover plate 7 held in place by a screw 8 and in this plate as well as in the opposite or rear side of the casing 4 are journaled two relatively small alined spindles 9 and

50 9^a, each of which within the casing has an arm 10 extending at right angles and having its extremity 11 extended parallel with its body portion 9. Outside of the casing each of these spindles has fixed to it an arm 55 or thread-controlled finger 12 having a thread-engaging loop 13 designed to coöper-

ate with a fixed yarn finger 14 and having mounted on it an adjustable weight 15 tending to swing it from the position shown in full lines in Fig. 1 to that shown in dotted 60 lines.

Under conditions of operation the yarn or thread extends in the lines $x-x$. Figs. 1 and 2, between the loops of the fingers 12 and 14 and holds the finger 12 in the 65 position shown in Fig. 1 in full lines, with the spindles 9 and 9^a and the arms 10 and 11 in the positions shown in Fig. 3. Inside the casing I mount a trigger lever 16 pivoted at 17 to a suitable supporting block 17^a and having an arm at right angles to its body extended adjacent the projecting offset arms 11 of the spindles 9 and 9^a. Adjacent the junction of this angular arm with the body of said lever I form a hook 18 75 designed to coöperate with a pin 19 preferably of angular section projecting laterally from one end of an arm 20 which is pivoted to the lower part of the casing 21.

A suitable spring 22 acts on the trigger 80 lever 16 adjacent its pivot 17 so as to tend to retain it in engagement with the pin or projection 19 of said arm 20, and the latter adjacent its pivot 21 is formed with a longitudinally extending slot 23 in which is slid 85 able a pin or projection 24 extending laterally from one arm of a manually controlled setting lever 25 pivoted within the casing on a screw 26 and extending outside of the same through a slot 27 in one end thereof. 90 The arm of this lever, which projects outside of the casing is adapted to be moved by an operator and has connected to it a bolt 28 suitably guided in the casing and capable of being projected outside of the same so as 95 to enter one of the openings 3 in the relatively movable structure 2. A spring 29 acts on the lever 25 in such manner as to at all times tend to move it into such a position as to project this bolt. 100

Under conditions of use the threads $x-x$ are run through suitable guides 30 and between the fixed and movable fingers 12 and 14 so that the spindles 9 and 9^a are held in such positions that their arms 11 within 105 the casing do not press against the trigger lever 16. If now the projecting end of the lever 25 be moved upwardly from the position shown in Fig. 4, toward that shown in Fig. 3, its pin 24 will slide in the slot 23 and 110 so move the arm 20 as to cause its pin to engage the hooked end 18 of the lever 16

and ultimately enter said hook thereof, which thereafter holds the parts in their set positions with the bolt 28 held clear of the rotary element 2. The machine to which the device is attached may now be put in operation.

Under these conditions the trigger lever will remain set until one of the threads $x-x$ breaks or becomes slack, whereupon the responding thread-controlled finger 12 is released and under the action of its weight 15 moves with its spindle 9 or 9^a into the position indicated in dotted lines in Fig. 1. As a consequence of this movement, the projecting arm 11 of the spindle presses against the upwardly projecting arm of the trigger lever 16, raising its hooked end 18 out of engagement with the pin 19 thereby leaving the arm 20 free to be swung on its pivot 21 under the action of the spring 29 acting through the lever 25 and pin 24. This release of said lever 25 causes downward movement and a consequent projection of the bolt 28 so that it enters the rotary element 3 and by stopping its movement relatively to the casing 4 and fixed member 1, sets in operation suitable stopping mechanism such as a belt shifter or braking mechanism. The machine is thereupon almost instantly stopped so that there is no damage to the goods operated on, as otherwise occurs by reason of the continued operation or drifting of the machine. After the broken thread has been tied or a new thread has been placed between the fingers 12 and 13, or when slack has been taken up, the lever 25 may be again moved to the position shown in Fig. 3, thus releasing the bolt 28 from the rotary member 2 and permitting the machine to again be put in operation.

It is to be particularly noted that not only is my device exceedingly simple and substantial in construction but its nature is such that it constitutes a complete, portable and easily applied thread-controlled apparatus applicable to knitting machines of standard construction, without requiring material change. Moreover, as above indicated, it is characterized by its rapid, sensitive and certain action resultant upon the breakage or slackening of the thread. It is compact and of such a nature that it is not likely to get out of order or require frequent inspection or repairs.

55 I claim—

1. The combination in a stop motion of a casing; a bolt slidably mounted therein; a setting lever pivoted to said bolt and projecting outside of said casing; an arm pivoted at one end to the casing and having a longitudinally extending slot for the reception of a projection on said setting lever; a spring operative on the lever and tending to project the bolt; a hook coöperative with the

arm for holding it with the setting lever and 65 bolt in a set position; with a thread-controlled finger operative to move the hook to an arm-releasing position.

2. The combination in a stop motion of a supporting structure; a relatively fixed 70 thread finger thereon; a relatively movable thread finger coöperative with said first finger and having an operating arm; a weight on said second finger tending to swing it away from said first finger; a slide- 75 able bolt carried by the supporting structure; a spring actuated lever tending to project said bolt; and means including a pivotally mounted member movable by the operating arm of the second thread finger to 80 releasably retain the spring actuated lever and the bolt in a set position.

3. The combination in a stop motion of a casing; a spindle journaled in a wall thereof and having an arm inside of said casing; a 85 thread finger connected to the spindle outside of the casing and including two arms at an angle to each other; a weight on one of the arms of said thread finger tending to move it from a position in which it is normally held by a thread; a spring-actuated bolt; and mechanism in the casing normally holding the bolt in a set position and releasable by a movement of the spindle arm resulting from swinging of the thread finger 95 under the action of its weight.

4. The combination in a stop motion of a casing; a weighted thread finger having a movable arm in said casing; a spring-actuated hook lever having an arm extending in 100 position to be moved by the arm of the thread finger; a swinging arm in the casing pivoted thereto adjacent one end and having a pin projecting from its opposite end in position to engage the hook of said lever; a 105 setting lever extending into the casing and having a pin operative in an elongated slot of said arm; a bolt connected to said latter lever and slidably guided in an opening of the casing; with a spring acting on the setting lever and tending to move it into a 110 position to project said bolt.

5. The combination of a relatively flat casing; a slidable bolt projectable therefrom; a spring-actuated setting lever connected to 115 said bolt and having a projecting pin; an arm having a projection and formed with a slot for the reception of the pin of the setting lever; a second lever in the casing having a hook for engagement with the projection of said arm; two spindles respectively having arms in the casing positioned to actuate said hook lever; with weighted thread fingers respectively connected to said spindles and fixed fingers mounted to coöperate with 125 threads to normally hold the weighted fingers from movement.

SAMUEL H. GOLDSTEIN.
